CLAIM

I claim, the ornamental design for the sun visor mounted cigarette lighter holder, as shown and described.

DESCRIPTION

FIG. 1 is a front elevational view of the sun visor mounted cigarette lighter holder showing my new design;

FIG. 2 is a rear elevational view of the sun visor mounted cigarette lighter holder thereof;

FIG. 3 is a left-side elevational view of the sun visor mounted cigarette lighter holder thereof, the right-side elevation view being a mirror image;

FIG. 4 is a top plan view of the sun visor mounted cigarette lighter holder thereof;

FIG. 5 is a bottom plan view of the sun visor mounted cigarette lighter holder thereof; and,

FIG. 6 is a perspective view of the sun visor mounted cigarette lighter holder thereof.
